13 Claims. (Cl. 166—65)

ABSTRACT OF THE DISCLOSURE

This disclosure is directed to means for securely connecting a well tool to a supporting member in such a manner that the well tool can be selectively disconnected therefrom should the tool be stuck in a well bore. In one manner of operation, application of a predetermined tension load on the supporting member will disconnect it from the stuck well tool. In another manner of operation, an electrical signal followed by a lesser predetermined tension load will disconnect the tool from its supporting member.

Accordingly, as will become apparent, it will be seen that invention relates to subsurface tools and is particularly concerned with apparatus for releasably suspending such tools from a cable.

In the operation of cable-suspended subsurface tools, such as various measuring and logging devices, subsurface conditions may cause the tool to become stuck. When this occurs, and the tool cannot be dislodged by application of a reasonably safe cable tension, it becomes necessary to disconnect the cable from the tool. Preferably, disconnection should occur at or adjacent the tool to facilitate retrieving the cable intact.

A cable that has parted by excess tension is not only itself damaged or lost but frequently interferes with subsequent removal of the tool, as by conventional fishing operations. It has, therefore, become conventional to provide a so-called "weak-point" connection between the cable and tool. This may be done by placing a weakened member in the line at or adjacent the cable head on the tool to provide a point of reduced tensile strength. When this is done and the tool becomes stuck, the application of sufficient tension on the cable will break the weak-point and disconnect the cable from the tool.

Such weak-points must, however, have sufficient tensile strength to support the static weight of the tool and any loads induced by drag in raising the tool as well as such additional tension as may reasonably be applied in any effort to dislodge the tool if it becomes stuck.

When the tool is downhole and the cable under tension, the point of greatest cable stress will be at or near the surface. For example, if a cable having an average tensile strength of 12,000-pounds is used in conjunction with a conventional weak-point having an average tensile strength of 6,200-pounds and 6,000-pounds of cable is within the bore hole when the tool sticks, additional tension will probably break the cable at or near the surface before the weak-point can be loaded beyond its tensile strength. Thus, a conventional weak-point may become inoperable if the tool becomes stuck at a substantial depth. Moreover, this particular problem with conventional weak-points tends to increase with operating depth since the footage which may be handled by the cable winch is greatly dependent upon cable diameter and, as diameter is reduced to increase footage, average tensile strength is sacrificed.

Further, the tension at which a conventional weak-point will break must necessarily be empirically deter-

2

mined. It is therefore necessary to actually break representative samples from each lot of weak-points manufactured, average the tensile force required to break them and take that average, plus or minus the deviation encountered (typically about five to ten percent) as the average tensile strength of each weak-point in the lot. Thus, in the hypothetical example just given, that weak-point might actually break several hundred pounds above or below 6,200-pounds. As a result, unless great pains are taken, there is always an uncertainty about the amount of cable tension that may be safely applied in attempting to dislodge a stuck tool, as well as the tension actually required to break the weak-point.

If in the course of tensioning the cable to break a conventional weak-point, the cable becomes key-seated (i.e., cuts into, and becomes bound by, the wall of a bore hole) as sometimes occurs in soft walled bore holes, before sufficient tension is developed to either dislodge a stuck tool or break the weak-point, release of the cable adjacent the tool is frustrated. When this occurs, the cable tension must be increased until the cable itself breaks. Such a break will be usually at or near the surface, but may be at a point of latent cable damage between the surface and the key-seat.

According to the present invention, release apparatus is provided for selectively releasing the cable by the application of any desired tension between minimum and maximum predetermined values, using release means which may be electrically operable from the surface, or simply by the application of a precisely predetermined maximum tension load.

More specifically, this invention is characterized by a mechanically disengageable member affording a releasable connection. Such a member may be provided by a collet having a plurality of radially disposed depending fingers terminating in angulated lugs which are securely gripped between movable opposed abutments within a cable head. An electrically releasable latching device retains one abutment normally engaged with one side of the collet lugs. The other abutment is normally positioned against the opposite side of the collet lugs and pre-loaded spring means are provided to prevent withdrawal of this other abutment unless and until a precisely predetermined tension is applied. Thus, cable release may occur selectively either when the latched abutment is released from engagement with the collet lugs in response to an electric signal or when the pre-loaded abutment is released from engagement with the collet lugs in response to application of a cable tension sufficient to overcome the pre-load springs.

More particular understanding of the invention may be had from the following description of one embodiment thereof which has been illustrated in the appended drawings, wherein:

- FIGURE 1 is an elevation view partly cut-away.
FIGURE 2 is a section view taken along line 2—2 of FIGURE 1.
FIGURE 3 is a section view taken along line 3—3 of FIGURE 2.
FIGURE 4 is a partial section showing the lower abutment in unlatched condition.
FIGURE 5 is a partial section showing the lower abutment moved downwardly from the collet lugs and the collet being withdrawn.
FIGURE 6 is a partial view showing the pre-loaded abutment and collet being withdrawn from locking engagement with the lower abutment.
FIGURE 7 is a partial view showing the pre-loaded abutment in completely withdrawn position, and the collet being released.

In the illustrated embodiment of this invention, as shown in FIGURE 1, a winch 10 carries a cable 11, which may conveniently include a plurality of electrical conductors 12. In operation, cable 11 typically passes from winch 10 under sheave 13 and over sheave 14, which is equipped with a tensiometer 15. After passing over sheave 14, cable 11 is connected to a cable head 16 from which a tool 17 may be suspended in a well bore by a threaded adapter 18.

As shown in FIGURE 1, cable head 16 includes a cylindrical housing 10 adapted to threadably receive adapter 18 at its lower end and to slidably receive a so-called boot 20 at its upper end. With continued reference to FIGURE 1, it will be seen that the central load supporting member 21 of cable 11 is secured to the upper end of a shank 22 by means of swaged socket 23. Then, as best seen in FIGURE 2, shank 22 extends coaxially into housing 19 with its lower end being formed into a collet 24 comprised of radially disposed depending fingers 25, each having outwardly facing angulated lugs 26.

With continued reference to FIGURE 2, it will be seen that collet lugs 26 are securely engaged between an upper abutment 27 and a lower abutment 28 which abutments are carried by and operable within a cylinder 29 received in housing 19. Cylinder 29 is supported in housing 19 by securing its flanged lower end 33 between internal shoulder 34 of housing 19 and the upper face 35 of plug 30. In turn, plug 30 is held by threading adapter 18 into the lower end of housing 19 until adapter 18 securely engages the lower end 32 and intermediate shoulder 31 of plug 30. At its upper end, cylinder 29 is sealed by a flexible bellows 36 the upper and lower ends of which are respectively secured to shank 22 and cylinder 29.

Intermediate the ends of cylinder 29, its bore is reduced in diameter to provide an internal annular shoulder 37. A collet sleeve 38 is slidably disposed around a reduced portion of shank 22 and collet 24. Lateral pin 39 in a slot at the upper end of sleeve 38 prevents the sleeve 38 from rotating relative to shank 22. Sleeve 38 has an enlarged lower end with a peripheral flange 40 which rests on shoulder 37 and an internally formed surface forming abutment 27 which engages the outer surfaces of collet lugs 26. A plurality of stacked Belleville washers 42 are disposed around the collet sleeve 38 and carried by the peripheral flange 40. A sleeve 43 is slidably disposed around the collet sleeve 38 and shank 20 and engages the upper end of the washer stack 42. An externally threaded adjusting nut 44 threadably engaged within the uppermost end of the bore of cylinder 29 is utilized to hold the washer stack 42 compressed and to urge flange 40 of the collet sleeve 38 downwardly against the upper side of shoulder 37 with a force of predetermined magnitude.

A cup-type latch housing 45 is disposed within the bore of cylinder 29 with its upper closed end engaged against the underside of shoulder 37. A latch carrier body 46 is slidably received in housing 45 and has a reduced-diameter frusto-conical portion which forms abutment 28 projecting upwardly from its upper end. Abutment 28 extends through an opening in the closed end of latch housing 45 and normally engages the inner surfaces of collet lugs 26. A plurality of depending fingers 48 are pivotally suspended within circumferentially spaced longitudinal slots in the annular body 46. At the lower free end of fingers 48, inwardly extending recesses 49 are provided to engage the inward side of a plurality of ball members 50 loosely received within holes through the side of body 46. Housing 45 has annular recesses 51 in which the outward side of the ball members 50 are normally received to secure the annular body 46 in its uppermost position.

Below body 46, a solenoid 52 is mounted within the housing 45 and includes a solenoid coil 53 having an upper pole piece 54. A tubular non-magnetic plunger 55 is mounted on an armature 56 in the position illustrated. Plunger 55 extends upwardly into the hollow interior of body 46 and has an enlarged non-magnetic upper portion

5 57. A plurality of balls 58 are loosely mounted in recessed portions of the enlarged plunger portion 57 and held in this position by a follower sleeve 59 which is biased upwardly by a light spring 60.

10 Each of the balls 58 are suitably positioned to be normally engaged against the inner surfaces of an offset tip portion 61 of the pivoted fingers 48 so long as the solenoid 52 is de-energized. Thus, so long as each set of balls 50 and 58 remains laterally opposite one another, the free ends of each of the pivoted fingers 48 are held therebetween to prevent body 46 from shifting downwardly, thereby maintaining abutment 28 firmly engaged against the inside of collet lugs 26.

15 Electrical circuitry suitable for energizing solenoid 52 is readily provided by electrical conductor lead 62 taken from the lower end of one of conductors 12 which normally extend between tool 17 and its associated surface equipment. When assembled, cylinder 29 is preferably hermetically sealed and oil-filled to achieve maximum protection from corrosive well-fluids, with the environmental pressure differential being compensated by the differential bellows 36.

20 To prevent inadvertent cable release by accidental actuation of solenoid 52, as hereinafter explained, a safety is provided. This safety takes the form of a weak-point designed to support a minimum load, e.g., the static load of a freely supported tool. Such weak-point comprises a replaceable rod 63 of non-magnetic material threadably connected at one end to shank 22 and extended through plunger 55 where it is connected to head 16 through plate 64 and housing 45 with a nut 65. Rod 63 has a reduced, weakened cross-section at 66 so as to break at, say 1,000-pounds tension plus or minus 10%. As best seen in FIGURE 2, so long as lugs 26 are engaged by abutments 27 and 28, no tension is applied to the rod 63 and the load is transmitted from the collet to abutment 27. However, when lugs 26 are released, the full load is immediately transferred to rod 63. If the load is above the minimum, rod 63 will break at 66.

25 In the event a tool carried from head 16 becomes stuck, cable 11 may be released from the head in either of two ways. If it is desired to release the cable 11 at a reduced tension, solenoid 52 is first electrically energized, e.g. by passing energizing current to solenoid 52 through that one 30 of conductors 12 in the cable 11 which is connected to conductor 62. When energized, armature 56 is pulled upwardly toward upper pole piece 54 to elevate the enlarged plunger portion 57. As the plunger portion 57 moves up, balls 58 roll upwardly along the inner surfaces 35 of the latch fingers 48 from their position shown in FIGURE 2 to the position shown in FIGURE 4. Once the inner balls 58 have cleared the offset tip portion 61 of fingers 48, the fingers are free to swing inwardly a sufficient radial distance to permit the outer balls 50 to 40 also move inwardly and roll out of the annular recesses 51. It will be appreciated, of course, that once the inner balls 58 have moved into their position as shown in FIG. 4, the body 46 is held in its uppermost position only by the biasing effect of spring 67.

45 Accordingly, whenever only a slight amount of tension is applied to cable 11, the upward pull on shank 22 will force the collet fingers 25 to contract as the upper abutment 27 cams the collet lugs 26 inwardly. As the collet lugs 26 move inwardly, the camming action of the 50 inner faces of the lugs on the frusto-conical surface of the lower abutment 28 will shift body 46 downwardly.

55 Once the body 46 has moved downwardly only a slight distance, the lower abutment 28 no longer restrains the collet lugs 26; and the fingers 25 are then retracted sufficiently to free the lugs from the upper abutment 27 as 60 shown in FIGURE 5. It will be appreciated that once the lugs 26 are free of abutment 27, the full load on the cable 11 is then applied to the weak-point or rod 63. Once the cable load has reached the predetermined design 65 tensile strength of the weakened portion 66 of rod 63,

the weakened portion will fail. Then, the shank 22 and all elements thereabove on the shank will be pulled out of the housing 19. As the shank 22 moves upwardly, the flexible bellows 36 are, of course, broken. As seen in FIGURE 1, the boot 20 is only splined to the housing 19 and will easily pull out of the housing.

If the electrical system should be inoperative or should there be some other reason for not utilizing it, the cable 11 can also be released mechanically by pulling on the cable. In this instance, sufficient tension must first be applied to overcome the oppositely directed predetermined load applied by the Belleville washers 42. Once this predetermined load has been equaled, the upper abutment 27 will shift very slightly upwardly away from flange 37. As additional tension is applied on the cable 11, the additional force will then be imposed on the weak-point 63 until the added force has reached the level necessary to break the weakened portion 66. Once this weakened portion 66 breaks, the additional force is suddenly transferred to the Belleville washers 42 which then further compress a sufficient distance to allow collet 24 and flange 40 to move upwardly. Once the collet fingers 25 have moved upwardly a short distance, the inner surfaces of the collet lugs 26 are no longer in contact with the lower abutment member 28 and the collet fingers 25 are free to contract and slip upwardly into collet sleeve 38. When this occurs, cable 11, shank 22, and collet 24 may be withdrawn from head 16 in the manner shown in FIGURES 6 and 7.

Among the several advantages of this invention is the capacity of the release apparatus to withstand jarring without premature release. This is because freeing of lugs 26 by releasing balls 50 requires that body 46 and enlarged plunger portion 57 move toward each other. Since jarring, whether from above or below, will produce forces acting in only one direction, this required counter-movement of body 46 and the enlarged plunger portions 57 will not occur. Additionally, the viscosity of the oil within cylinder 29 will dampen any movement of body 46 and plunger portion 57.

It should be noted that the springs 60, 67 and 69 will aid in holding the members with which they are engaged in position to maintain the apparatus latched. Moreover, these springs 60, 67 and 69 will permit the electrical release system to be tested before the apparatus is lowered into a well bore since once the solenoid 52 is de-energized, the springs will restore their respective members to their normal positions. It will also be appreciated that spring 60 and ball follower 59 will ensure that balls 58 are free to roll rather than having to slide upwardly. Thus, the load that the solenoid 52 must operate against is minimized by encountering rolling, rather than sliding, friction.

It will be appreciated that with the weak-point 63 the release force can be much more precisely known than with conventional systems since, unlike conventional mass-produced weak-points, the weak-point 63 will be designed to support only a few hundred pounds. By employing the apparatus of the present invention in the previous example, the weak-point 63 can be designed to have an average tensile strength of 1,200-pounds and a predetermined load of 5,000-pounds applied to the Belleville washers 42. Thus, assuming the margin of error in determining the breaking strength of the weak-point 63 to be 10%, the release point will vary only 120-pounds above or below the design release point of 6,200-pounds as contrasted with the wide range typical of conventional mass-produced weak-points designed for higher loads.

Devices embodying this invention might take various forms and may employ a variety of equivalent means. Thus, the collet means might be replaced with other connection means; the washer stack might be replaced with a spring or other pre-load means; a tool might be connected directly rather than through a cable head; a tool

might employ only the electrically operative release feature; or, when non-electrical cable is used a tool, might employ only the yieldable pre-loaded release feature.

Thus, the scope of the invention taught herein is much broader than the one embodiment illustrated and described, such description and illustration being given solely to facilitate further understanding of the invention by those skilled in the art to which it pertains. Accordingly, the invention will readily admit of other equally effective embodiments all of which are intended to be within the scope of the appended claims.

I claim:

1. In a subsurface tool adapted to be suspended from a cable extending to the surface, apparatus operable from the surface for releasing said tool from a cable, said apparatus comprising:

first and second co-engaging companion members respectively connected to said tool and adapted for connection to a cable;

means for releasably connecting said companion members including stop means on one of said companion members arranged and adapted to engage the other of said companion members for constraining said other companion member, said stop means being movable from a normal position in engagement with said other companion member for connecting said companion members to another position for disconnecting said companion members;

means for retaining said stop means in said normal position and operable from the surface and through a cable to release said stop means for movement to said other position;

and means for releasably securing said companion members including a breakable linking member normally fastening said companion members together.

2. As a sub-combination for use in a subsurface tool adapted to be suspended from a cable extending to the surface, apparatus operable from the surface for releasing such a tool from a cable, said apparatus comprising:

first and second co-engaging companion members respectively adapted for connection to a tool and a cable;

means for releasably connecting said companion members including first and second stop means on one of said companion members for constraining the other of said companion members, said first stop means being movable independently of said second stop means from a normal position in engagement with said other companion member for connecting said companion members to another position for disconnecting said companion members;

force-applying means retaining said first stop means in said normal position and holding said first stop means engaged with said other companion member with a force of predetermined magnitude; said force-applying means being responsive to an oppositely-directed force applied through said second companion member in excess of said predetermined magnitude to overcome said force-applying means and move said first stop means to said other position.

3. In a subsurface tool adapted to be suspended from a cable extending to the surface, apparatus operable from the surface for releasing said tool from a cable, said apparatus comprising:

first and second co-engaging companion members respectively connected to said tool and adapted for connection to a cable;

means for releasably connecting said companion members including first and second stop means on one of said companion members for constraining the other of said companion members, said first stop means being movable independently of said second stop means from a normal position in engagement with said other companion member for connecting

said companion members to another position for disconnecting said companion members; and spring means retaining said first stop means in said normal position and urging said first stop means toward said second stop means with a spring force of predetermined magnitude, said spring means being yieldable in response to an oppositely-directed force applied through said second companion member in excess of said predetermined magnitude to overcome said spring force and move said first stop means to said other position.

4. In a subsurface tool adapted to be suspended from a cable extending to the surface, apparatus operable from the surface for releasing said tool from a cable, said apparatus comprising:

first and second co-engaging companion members respectively connected to said tool and adapted for connection to a cable; means for releasably connecting said companion members including first and second stop means on one of said companion members for constraining the other of said companion members, said first stop means being movable from a normal position in engagement with said other companion member for connecting said companion members to another position for disconnecting said companion members; spring means retaining said first stop means in said normal position and urging said first stop means toward said second stop means with a force of predetermined magnitude, said spring means being yieldable in response to an oppositely-directed force on said first stop means and in excess of said predetermined magnitude to move said first stop means to said other position;

and means for releasably securing said companion members including a breakable member normally fastening said companion members together.

5. In a subsurface tool adapted to be suspended from a cable extending to the surface, apparatus operable from the surface for releasing said tool from a cable, said apparatus comprising:

first and second co-engaging companion members respectively connected to said tool and adapted for connection to a cable;

means for releasably connecting said companion members including first and second stop means on one of said companion members arranged and adapted to engage and constrain the other of said companion members, said first stop means being movable independently of said second stop means from a normal position in engagement with said other companion member for connecting said companion members to another position for disconnecting said companion members;

means for retaining said first stop means in said normal position;

and means responsive to an electrical signal for disabling said retaining means and freeing said first stop means for movement to said other position to disconnect said companion members.

6. In a subsurface tool adapted to be suspended from a cable extending to the surface, apparatus operable from the surface for releasing said tool from a cable, said apparatus comprising:

first and second co-engaging companion member respectively connected to said tool and adapted for connection to a cable;

means for releasably connecting said companion members including first and second stop means on one of said companion members arranged and adapted to engage and constrain the other of said companion members, said first stop means being movable from a normal position in engagement with said other companion member for connecting said companion

members to another position for disconnecting said companion members; means for retaining said first stop means in said normal position;

means responsive to an electrical signal for disabling said retaining means and freeing said first stop means for movement to said other position to disconnect said companion members;

and means for releasably securing said companion members including a breakable linking member normally fastening said companion members together.

7. In a subsurface tool suspended from a cable extending to the surface, apparatus operable from the surface for releasing said tool from said cable, said apparatus comprising:

first and second co-engaging companion members respectively connected to said tool and said cable; means for releasably connecting said companion members including first and second movable stop means on one of said companion members arranged and adapted to engage the other of said companion members for constraining said other companion member, each of said stop means being independently movable from a normal position in engagement with said other companion member for connecting said companion members to another position for disconnecting said companion members;

and first and second means for respectively retaining said first and second stop means in their said normal positions, each of said retaining means being selectively operable from the surface and through said cable to release their associated one of said first and second stop means for independent movement to their said other positions.

8. In a subsurface tool adapted to be suspended from a cable extending to the surface, apparatus operable from the surface for releasing said tool from said cable, said apparatus comprising:

first and second co-engaging companion members respectively connected to said tool and adapted for connection to a cable;

means for releasably connecting said companion members including first and second movable stop means on one of said companion members arranged and adapted to engage the other of said companion members for constraining said other companion member, each of said stop means being independently movable from a normal position in engagement with said other companion member for connecting said companion members to another position for disconnecting said companion members;

and first and second means for respectively retaining said first and second stop means in their said normal positions, each of said retaining means being selectively operable from the surface and through a cable to release their associated one of said first and second stop means for independent movement to their said other positions;

and means for releasably securing said companion members including a breakable linking member normally fastening said companion members together.

9. In a well tool adapted to be suspended in a well bore from a cable having electrical conductor means and extending to the surface of the ground, selectively-operable release apparatus comprising:

first and second co-engaging companion members respectively connected to said tool and adapted for connection to such a cable;

means for releasably connecting said companion members including first and second movable stop means on one of said companion members arranged and adapted to engage the other of said companion members for constraining said other companion member, each of said stop means being movable from a normal position in engagement with said other com-

panion member for connecting said companion members to another position for disconnecting said companion members;

first means for retaining said first stop means in said normal position electrical means operative from the surface and through such a cable to actuate said first retaining means to a position for selectively releasing said first stop means for movement to said other position; and

spring means retaining said second stop means in said normal position for urging said second stop means toward said first stop means with a force of a predetermined magnitude, said spring means being yieldable in response to a force applied through said second companion member in excess of said predetermined magnitude to overcome said spring force and selectively move said second stop means to said other position.

10. In a subsurface tool adapted to be suspended from a cable extending to the surface, apparatus operable from the surface for releasing said tool from a cable, said apparatus comprising:

first and second co-engaging companion members respectively connected to said tool and adapted for connection to a cable;

means for releasably connecting said companion members including first and second stop means on one of said companion members arranged and adapted to engage the other of said companion members for constraining said other companion member, each of said stop means being independently movable from a normal position in engagement with said other companion member for connecting said companion members to another position for disconnecting said companion members;

latch means for retaining said first stop means in said normal position and operable from the surface and through a cable to free said first stop means for movement to said other position;

and spring means retaining said second stop means in said normal position for urging said second stop means toward said first stop means with a force of predetermined magnitude, said spring means being yieldable in response to a force directed away from said first stop means acting on said second stop means and in excess of said predetermined magnitude to move said second stop means to said other position.

11. In a subsurface tool suspended from a cable extending to the surface, apparatus operable from the surface for releasing said tool from said cable, said apparatus comprising:

first and second co-engaging companion members respectively connected to said tool and said cable;

means for releasably connecting said companion members including first and second movable stop means on one of said companion members arranged and adapted to engage the other of said companion members for constraining said other companion member, each of said movable stop means being movable from a normal position in engagement with said other companion member for connecting said companion members to another position for disconnecting said companion members;

latch means for retaining said first stop means in said normal position and operable from the surface and through said cable to free said first stop means for movement to said other position;

spring means retaining said second stop means in said normal position for urging said second stop means toward said first stop means with a force of predetermined magnitude, said spring means being yieldable in response to a force acting on said second stop means and in excess of said predetermined magnitude to move said second stop means to said other position;

and means for releasably securing said companion members including a breakable linking member normally fastening said companion members together.

12. In a subsurface tool adapted to be suspended from a cable extending to the surface, apparatus operable from the surface for releasing said tool from said cable, said apparatus comprising:

first and second co-engaging companion members respectively connected to said tool and said cable; means for releasably connecting said companion members including first and second movable stop means on one of said companion members arranged and adapted to engage the other of said companion members for constraining said other companion member, each of said stop means being movable from a normal position in engagement with said other companion member for connecting said companion members to another position for disconnecting said companion members;

latch means for retaining said first stop means in said normal position and including means responsive to an electrical signal for disabling said latch means and moving said first stop means to said other position;

and spring means for retaining said second stop means in said normal position and including means responsive to a tension of predetermined magnitude on said other companion member for disabling said spring means and moving said second stop means to said other position.

13. As a sub-combination for use in a subsurface tool adapted to be suspended from a cable extending to the surface, apparatus operable from the surface for releasing such a tool from such a cable, said apparatus comprising:

first and second co-engaging companion members respectively adapted for connection to a tool and a cable;

means for releasably connecting said companion members including first and second movable stop means on one of said companion members arranged and adapted to engage the other of said companion members for constraining said other companion member, each of said stop means being movable from a normal position in engagement with said other companion member for connecting said companion members to another position for disconnecting said companion members;

latch means for retaining said first stop means in said normal position and including means responsive to an electrical signal for disabling said latch means and moving said first stop means to said other position; spring means for retaining said second stop means in said normal position and including means responsive to a tension of predetermined magnitude on said other companion member for disabling said spring means and moving said second stop means to said other position;

and means including a breakable member of predetermined strength for normally connecting said companion members independently of said stop means.
